Primary Examiner — Melanie H Tung*Assistant Examiner* — Kyra S Buenaventura(74) *Attorney, Agent, or Firm* — Morgan, Lewis & Bockius LLP(57) **CLAIM**

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.
